3 Claims. (Cl. 179—171.5)

In order to save energy in the modulation of high frequency currents various methods have been devised. According to one of these methods modulated high frequency is amplified to a high degree by means of an anode voltage which is applied to the high frequency power amplifier and which is varying in accordance with the modulation rhythm. This method is of merely theoretical value, not having been carried into effect so far.

In order to improve the efficiency of this method the invention suggests to combine therewith the well-known method of the so-called Hapug-modulation, that is, a modulation which involves variation of the carrier wave. In this way not only the energy conditions, but also the conditions of operation are improved, as will appear from the following.

As is well-known, modulating methods are generally required to effect a modulation without distortion. The aforesaid method of applying to the high frequency power amplifier a continuous anode voltage which is varying in the modulation rhythm does not fulfil this requirement, but will fulfil it to a certain degree if combined with the Hapug-method. If, however, the modulation is desired to be extremely well qualified then according to a further feature of the invention it is convenient at the same time to effect at the grid of the high frequency power stage a counter coupling of the low frequency alternating anode voltage, an additional modulation that might arise through anodal retroaction being avoided in this way. If desired, the method using such counter coupling may be employed in conjunction with the aforesaid modulating method even without the aid of the Hapug-method.

The invention will be understood from the following description, reference being had to the accompanying drawing which is a wiring diagram of one embodiment of the invention. In this embodiment both the Hapug-method and the counter-coupling method are employed.

Part 1 schematically represents the prestages of a transmitter, while part 2 is the modulating stage. The grid of part 2 is influenced by the method of grid voltage modulation. To such end a transformer 3 is included in the grid circuit of part 2 and is located also in the output circuit of a modulation amplifier 4. 5 indicates a microphone. The same stage is influenced also by the displacement of the working point, that is, the displacement peculiar to the Hapug-method. For this purpose a resistance 6 is disposed in the

grid biasing circuit. To resistance 6 a continuous voltage, generated by a member 7, is conveyed, this voltage fluctuating in accordance with the mean modulation rhythm, that is to say, in accordance with the mean value of the modulation amplitude. Member 7 in a well-known manner comprises a rectifier arrangement and smoothing means in order to derive from the modulation currents—the input circuit of member 7 is likewise connected to the microphone 5—a continuous voltage which is fluctuating in accordance with the mean value of the modulation amplitudes. Behind stage 2 high frequency amplifier tubes 8 and 9 are arranged. Tube 8 is merely in the nature of an amplifier for the modulated Hapug-controlled high frequency currents. Tube 9, however, is to be a high frequency power end stage. The anode voltage is conducted to this stage over a low frequency transformer 10. The modulating voltage is superimposed on the anode voltage with the aid of a transformer. To such end microphone 5 is connected to an amplifier 11 which acts to influence the grid of a low frequency Class B amplifier 12 of the push-pull type. This amplifier is employed in order to provide for the necessary great efficiency with which the modulating voltage is acting on the anode of tube 9.

In accordance with another feature of the invention amplifier 12 may contrarily to the normal modulation amplifiers of the class B type operate without closed circuit connection; it is to be understood here that distortions may be allowed to arise to some extent since they are compensated by the said counter coupling.

In order to avoid the aforesaid anodal retroaction the best course will be to derive a counter voltage from the output transformer of amplifier 12 with the aid of a winding 13 and to convey this voltage to the grid of tube 9 over a transformer 14. It is of course possible also to take this counter voltage from other suitable points.

By A, connections to the anode battery, and by G, connections to the grid battery are denoted.

The here described arrangement entails a considerable saving in energy, as will appear from the following statement: The energy received from a public supply by a 100 k. w. transmitter provided with the hitherto known anode voltage control (normal anode voltage modulation, not the aforesaid amplifier for modulated high frequency energy) is with $m=0$ about 340 k. w., with $m=0.3$ about 360 k. w. and with $m=1$ about 520 k. w., m being the degree of modulation. In the novel arrangement, however, with a re-

mainder or at-rest value $\rho=0.6$ of the carrier the respective values are in the case of $m=0$ about 240 k. w., $m=0.3$ about 300 k. w., $m=1$ about 450 k. w. Thus, as compared with 5 the normal grid voltage modulation a saving of about 200 k. w. is afforded, while the saving over the anode voltage modulation is about 160 k. w.

In this connexion it may be mentioned that 10 it is well-known per se to effect the Hapug-displacement of the working point by influencing the anode voltage of the final stage. This method, however, has the drawback that the anode voltage source must be worked upon directly, that 15 is to say, in the case of the customary grid controlled rectifiers the grid control must be so influenced as to displace the ignition point in accordance with the mean value of the modulation. Such influencing, however, can not be 20 accomplished with a sufficient quickness, this fact being due to an insufficiency of the means available in this regard. Apart from this, the modulating tube is by the invention better utilized than has been the case heretofore since 25 as stated the class B amplifier allows of admitting greater distortions.

What is claimed is:

1. A high frequency transmitter arrangement comprising a source for producing a high frequency carrier, means for modulating said high frequency carrier with a modulation voltage, means for fluctuating said high frequency carrier in dependency upon the mean value of said modulation voltage, a power amplifier, means for applying to said power amplifier the modulated 30

and fluctuated high frequency carrier, and means for varying the anode direct current potential of said power amplifier dependent upon said modulation voltage.

2. A high frequency transmitter arrangement 5 comprising a source for producing a high frequency carrier, means for modulating said high frequency carrier with a modulation voltage, means for fluctuating said high frequency carrier in dependency upon the mean value of said 10 modulation voltage, a power amplifier, means for applying to said power amplifier the modulated and fluctuated high frequency carrier, and means for varying the anode direct current potential of said power amplifier dependent upon 15 said modulation voltage, said last mentioned means being a class B amplifier of the push-pull type.

3. A high frequency transmitter arrangement 20 comprising a source for producing a high frequency carrier, means for modulating said high frequency carrier with a modulation voltage, means for fluctuating said high frequency carrier in dependency upon the mean value of said 25 modulation voltage, a power amplifier, means for applying to said power amplifier the modulated and fluctuated high frequency carrier, means for varying the anode direct current potential of said power amplifier dependent upon 30 said modulation voltage, and counter coupling means for conveying said modulation voltage to the grid of said power amplifier.
